CHERRY PITTER

Robert H. Frank, Philadelphia, Pa., assignor to
The Enterprise Manufacturing Co. of Pennsylvania,
Philadelphia, Pa., a corporation of Pennsylvania

Application October 9, 1952, Serial No. 21,772

Term of patent 14 years

(Cl. D89—1)

To all whom it may concern:

Be it known that I, Robert H. Frank, a citizen of the United States, residing in Philadelphia, county of Philadelphia, State of Pennsylvania, have invented the new, original, and ornamental Design for a Cherry Pitter, of which the following is a specification, reference being had to the accompanying drawing, forming a part hereof, in which:

Fig. 1 is a perspective view of a cherry pitter, showing my new design;

Fig. 2 is a side elevational view of the cherry pitter;

Fig. 3 is a plan view of the cherry pitter from the underside thereof in the position shown in Fig. 2; and

Fig. 4 is an end elevational view of the cherry pitter as viewed from the left hand end in Fig. 2.

I claim:

The ornamental design for a cherry pitter, substantially as shown.

ROBERT H. FRANK.
